[57] CLAIM

The ornamental design for a cosmetic compact, as shown and described.

DESCRIPTION

FIG. 1 is a perspective view of a cosmetic compact showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a side elevational view thereof, the side opposite being identical to the side shown;

FIG. 7 is a side elevational view shown in an open condition, the side opposite being a mirror image of the side shown;

FIG. 8 is a top perspective view thereof;

FIG. 9 is a top plan view of one of the cosmetic product cartridge elements of the design seen in FIG. 8, shown separately for clarity of illustration;

FIG. 10 is a bottom plan view thereof; and,

FIG. 11 is a side elevational view thereof.

The stippling in FIGS. 8 and 9 represents the color contrasting surface of a cosmetic product.
